FIRE EXTINGUISHER DISCHARGE DEVICE

Frank B. Allen, Towaco, N. J., assignor to C-O-Two Fire Equipment Company, Newark, N. J.

Application February 19, 1953, Serial No. 337,724

3 Claims. (Cl. 169—11)

The present invention relates to fire extinguishing, and particularly to an improved large capacity discharge device particularly suitable for use with low temperature carbon dioxide extinguishing fluid.

Carbon dioxide for fire extinguishing purposes is stored in refrigerated containers at greater than atmospheric pressure for economy of storage. The pressure is maintained adequate to provide a high rate of discharge through a piping system to a hazard to be protected against fire. However, if the carbon dioxide at its storage pressure is discharged without a suitable velocity reducing device, air may be entrained to reduce the effectiveness of the carbon dioxide, in addition, the high velocity of the carbon dioxide may be such as to cause the scattering of burning combustible material.

Heretofore, various types of discharge devices have been provided to attain the desired reduced velocity of the discharge, among which is the construction disclosed in S. E. Allen et al. Patent No. 1,993,696, issued March 5, 1935. The present invention is an improvement over that described in the Allen et al. patent in that a somewhat more simplified construction is disclosed. Prior constructions have provided a discharge device including a closed end tubular member extending into the shield, the side wall of the tubular member being provided with a plurality of orifices. Such a construction is shown in Ensminger application Serial No. 226,047, filed May 12, 1951, now Patent No. 2,655,219, issued October 13, 1953. The present construction is particularly suitable for large capacity units in which lightness of weight is very important. Further, the new construction may be fabricated by modern production machinery and thus may be sold at a comparatively lower price.

An object of the invention is to provide a discharge device which is simple and economical in manufacture, efficient in operation and durable in use.

In accordance with the invention this is accomplished by providing a discharge device in which the body thereof may be formed of a bushing, and the discharge member and shield may be pressed or drawn.

Other objects and advantages of the invention will be apparent from the following description and from the accompanying drawing which shows an embodiment of the invention.

In the drawing:

Figure 1 is a side view of a discharge device in accordance with the invention, a portion thereof being broken away to show the internal construction.

Figure 2 is an end view looking from left to right of the discharge device shown in Figure 1.

Figure 3 is a vertical sectional view of the body or bushing member of the device.

Figure 4 is a vertical sectional view of a retaining member.

Figure 5 is a vertical sectional view of the nozzle or discharge member of the device.

Referring to the drawing, there is shown in Figure 1 a discharge device 1 for carbon dioxide fire extinguishing

2

fluid including a directing tube means 2, a housing or bushing member 3, a discharge or nozzle member 4, and a retaining ring nut member 5.

The directing tube 2 may be made of any suitable material such as metal, laminated plastic, or other light-weight material strong enough to withstand ordinary usage and may be stamped or pressed to the desired shape. Preferably, the directing tube means 2 is formed with straight side walls 6, although other configurations such as outwardly tapering side walls might be used. The open end of the directing tube means may be provided with a flange, if desired, for attaching the directing tube means about an opening in the wall. Closed end 7 of the directing tube means is apertured to fit over the end of the bushing member 3.

The bushing member 3 may be made of metal or laminated plastic and is formed with a passage 9 extending therethrough. Adjacent end 10 of the bushing 3, the passage 9 is made of reduced cross-section to provide a shoulder 11. At the end 10 of the bushing member 3 is an axially extending extension 12 for holding the directing tube in position. The other end 14 of the bushing member 3 is internally threaded as indicated at 15 to engage with a piping for a conventional fire extinguishing system. The directing tube means 2 is secured in position on the end 10 of the bushing member 3 with the end 7 of the directing tube abutting against the end edge of the bushing member, the aperture and the directing tube 2 being of a diameter so that a close fit is had over the axially extending extension 12. The outer end of the extension 12 is then turned outwardly over the edge of the wall of the aperture in the directing tube to secure the directing tube firmly in position on the bushing member 3.

The nozzle member 4 is preferably made of metal although any other suitable light-weight material may be used. The nozzle member 4 may be stamped or pressed of sheet metal and is formed into a generally tubular shape with side wall 16 and a closed wall 17. The open end of the nozzle member 4 is turned outwardly to provide a flange 19. A plurality of equally spaced apertures 20 are made in the nozzle member adjacent the closed end 17 thereof. The diameter of the nozzle member 4 is such that a snug fit is provided with the inner wall of the bushing member 3 and the shoulder 11 of the bushing 3, the flange 19 abutting against the shoulder so as to hold the tubular member in position.

The retaining ring nut member 5 is provided with a threaded outer surface 21 to engage in the threaded surface 15 of the bushing member 3. The inner diameter of the retaining nut member 5 is made the same as the inner diameter of the nozzle member 4 in order that there is no restriction in the passage for the discharged fluid from the piping system to the apertures 20. Notches 22 are made in the edge of the retaining ring nut member for engagement by a tool for tightening the nut in position.

In assembling the discharge device 1, the directing tube means 2 is pressed in position on the bushing member 3, and the axially extending extension 12 turned over to secure the directing tube in position. The nozzle member 4 is then inserted through the threaded portion 14 so that the flange 19 abuts against the shoulder 11, and the retaining ring nut member 5 is secured in position.

While the invention is described and illustrated with reference to specific embodiments thereof, it will be understood that other embodiments may be resorted to without departing from the invention. Therefore, the form of the invention set out above should be considered as illustrative and not as limiting the scope of the following claims.

I claim:

1. A discharge device for carbon dioxide fire extinguishing fluid comprising directing tube means with a

closed apertured end, a bushing member having a passage therethrough with a threaded portion, shoulder means in the passage, a thin-walled nozzle member formed into a tubular shape with a closed end and having a plurality of apertures in its side wall adjacent its closed end, flange means about the open end of the nozzle member abutting against the shoulder, and a retaining member threadedly engaged with the wall of the bushing member holding the nozzle in position.

2. A discharge device for carbon dioxide fire extinguishing fluid comprising directing tube means with a closed apertured end, a bushing member having a passage therethrough, a reduced portion of the passage defining shoulder means, the passage wall threaded at the outer end thereof, an axially extending flange for the bushing member turned over the wall of the aperture in the directing tube holding the tube in position, a thin-walled one-piece nozzle member formed into a tubular shape with a closed end and having a plurality of apertures in its side wall adjacent its closed end, the open end of the nozzle member turned outwardly to form a flange abutting against the shoulder, and a retaining ring member threadedly engaged with the threaded bushing passage wall holding the nozzle member in position.

3. A discharge device for carbon dioxide fire extinguishing fluid comprising directing tube means with a closed apertured end, a straight bushing member with a

passage therethrough, a reduced portion of the passage adjacent one end thereof defining a shoulder, the other end of the passage threaded, an axially extending flange at the one end of the bushing member turned over the wall of the aperture in the directing tube securing the wall against the end of the bushing member holding the directing tube in position, a thin-wall one-piece nozzle member formed into tubular shape with a closed end and having a plurality of apertures in its side wall adjacent its closed end, the open end of the nozzle member turned outwardly to form a flange abutting against the shoulder, the tubular member projecting into the directing means a sufficient distance providing an unrestricted discharge from the nozzle apertures into the directing means, the nozzle wall thickness being insufficient to appreciably decrease the size of the passage in the bushing member, and a thin-walled retaining ring member threadedly engaged with the threaded bushing passage wall, the retaining ring having a passage therethrough of approximately the same diameter as the nozzle member so as to provide an unrestricted passage to the nozzle apertures.
